UNITED STATES PATENT OFFICE

SAMUEL B. BOWMAN, OF ZANESVILLE, OHIO, ASSIGNOR TO HAZEL-ATLAS GLASS CO., OF WHEELING, WEST VIRGINIA, A CORPORATION OF WEST VIRGINIA

DESIGN FOR A HOLLOW GLASS BRICK

Application filed June 23, 1931. Serial No. 40,805. Term of patent 14 years.

all whom it may concern:

Be it known that I, SAMUEL B. BOWMAN, a citizen of the United States, residing at Zanesville, in the county of Muskingum and State of Ohio, have invented a new, original, and ornamental Design for Hollow Glass Brick for Construction Purposes, of which the following is a specification, reference be-

ing had to the accompanying drawing, forming part thereof.

The figure is a perspective view of my new design.

I claim:

The ornamental design for a hollow glass brick, as shown.

SAMUEL B. BOWMAN.
